United States Patent Office

Des. 181,273
Patented Oct. 29, 1957

181,273

COMBINED CONDIMENT DISPENSERS AND RACK THEREFOR

Samuel J. Boker, Brooklyn, N. Y., assignor to Nova-Plas
Manufacturing Co., Inc., Brooklyn, N. Y.

Application October 10, 1956, Serial No. 43,309

Term of patent 14 years

(Cl. D44—22)

Fig. 1

FIG. 2

FIG. 3

FIG. 4

FIG. 5

Fig. 1 is a perspective view of my combined condiment dispensers and rack therefor, showing my new design;

Fig. 2 is a rear view, in elevation, thereof;

Fig. 3 is an end view thereof;

Fig. 4 is a rear view of one of the condiment dispenser elements; and

Fig. 5 is a side elevation of the latter.

I claim:

The ornamental design for combined condiment dispensers and rack therefor, substantially as shown.
